UNITED STATES PATENT OFFICE.

WILLIAM ROLLAR, OF CHICAGO, ILLINOIS; ROBERT TARRANT EXECUTOR
OF SAID ROLLAR, DECEASED.

FEED-WATER HEATER.

SPECIFICATION forming part of Letters Patent No. 291,538, dated January 8, 1884.

Application filed November 24, 1882. (No model.)

To all whom it may concern:

Be it known that I, WILLIAM ROLLAR, a citizen of the United States, residing at Chicago, in the county of Cook and State of Illinois, have invented certain new and useful Improvements in Feed-Water Heaters for Boilers; and I hereby declare the following to be a full, clear, and exact description of the same.

10 Divested for the present of all minor details of construction, a general description of my improved device, its method of operation, and the results accomplished is as follows: Within a strong metallic cylinder or shell, which may 15 be either vertical or horizontal, having an inlet-pipe at one end connected to the steam-exhaust of the engine, and having an outlet at the opposite end, I support a worm a little smaller in diameter than the interior of the 20 cylinder, and extending nearly or quite from end to end of the same, with an inlet and an outlet, preferably both, at the same end of the cylinder, the former leading from the feed-pump, and the latter leading to the boiler. I 25 also employ, suspended centrally within the coil, a hollow sheet-metal cylinder of smaller diameter than the interior of the coil, also somewhat less in length than the coil, thus making it shorter than the interior of the shell, 30 and preferably having that one of its ends which is adjacent to the steam-inlet of the cylinder made conical. With this construction the exhaust-steam from the engine, entering the cylinder, flows through the same in contact with the coil of pipe, through which the 35 feed-water circulates on its way to the boiler, thus heating the water to a high temperature. The steam, having performed its work, finds its way out, considerably condensed of course, 40 through the outlet provided for that purpose. The effect of the interior suspended cylinder operating in conjunction with an inclosing-cylinder is to cause the hot steam to impinge with more force upon the interposed coil than 45 would be the case if it were omitted. The conical end of this cylinder tends to divide the steam without resistance.

My invention, as may be derived from the foregoing outline, consists, first, in employing, in a feed-water heater, a worm for the

passage of the feed-water, inclosed within a cylinder through which the exhaust-steam passes, and combining with the inclosing-cylinder and worm, as above, a suspended interior cylinder of smaller diameter than the worm, 55 and shorter than the interior of the shell.

It consists, also, in certain details of construction and combinations of parts, all as herein-after more fully set forth.

In the drawings, Figure 1 is a central longitudinal section of my device, and Fig. 2 a transverse section on the line 2 2 of Fig. 1.

A is the inclosing cylinder or shell, which I make light and strong, of wrought-iron, and B the worm, which I prefer to make of copper tubing, supported within the shell. To support the worm in position I employ three bars, v, connecting the heads u of the shell by being firmly secured thereto by nuts t, and so disposed as to touch each coil of the worm at 60 three equidistant points. The worm is secured to these bars by means of metal strips s on the inside of the worm, firmly attached to the bars u above and below the worm, and also between the consecutive coils thereof, by means of 65 nut-bolts r, which operate to draw the strips closely about the tubing, as shown. The inlet and outlet of the worm are both at the upper end of the shell when the latter is vertical, as represented in the drawings, the pipe passing 70 down in a coil from the inlet, and then back in a straight line inside the coil to the outlet. At both the inlet and outlet it is coupled to a pipe on the outside of the head by a suitable coupling device. The steam is admitted 75 into the cylinder by way of the pipe h and discharged by way of the pipe i. When the cylinder lies horizontally, the drip-pipe f will of course be placed upon the lower side instead of upon the lower end, as shown. The 80 interior cylinder, D, is secured in position by means of metal braces g—three at each end—each bolted or riveted to it, as shown, and connected at its outer end to the adjacent bar v by one of the nut-bolts r, which fasten the 85 strips s to the bars.

By the construction above described, the weight of the heater in proportion to its size is reduced to the minimum, all joints and connections are outside and easy of access, and 90 95 100

the device works equally well whether horizontal or perpendicular, and can be set up in a corner or swung under the floor, out of the way.

5 What I claim as new, and desire to secure by Letters Patent, is—

1. In a feed-water heater, the combination of the shell A, having an inlet and an outlet pipe for the passage of the exhaust-steam from the engine, worm B, supported within the shell, and provided with an inlet and an outlet through the shell, for the passage of the water on its way to the boiler, and the cylinder D, suspended within the confines of the worm, and shorter than the interior of the shell A, substantially as described.

15 2. In a feed-water heater, the combination of the shell A, provided with an inlet and outlet for steam, worm B, inclosed within the

shell, and provided with an inlet and outlet 20 through the shell for water, bars v, extending longitudinally through the shell, and secured to the heads thereof, and the strips s and nut-bolts r, securing the worm to the bars v, substantially as described.

25 3. In a feed-water heater, the combination, with the shell A, having an inlet and an outlet pipe, worm B, provided with an inlet and an outlet through the shell, bars v, extending longitudinally through the shell, and secured to the heads thereof, and the metal strips s and nut-bolts r, securing the worm to the bars v, of the conical-ended cylinder D and braces g, substantially as described.

WM. ROLLAR.

In presence of—

C. C. LINTHICUM,

W.M. H. DYRENFORTH.
